UNITED STATES PATENT OFFICE.

LUCIUS E. WEAVER, OF EAST HAMPTON, CONNECTICUT, ASSIGNOR TO SUMMIT THREAD COMPANY, OF EAST HAMPTON, CONNECTICUT, A CORPORATION OF MAINE.

SEWING-MACHINE SHUTTLE.

Application filed December 3, 1923. Serial No. 678,159.

To all whom it may concern:

Be it known that I, LUCIUS E. WEAVER, a citizen of the United States, residing at East Hampton, in the county of Middlesex and State of Connecticut, have invented new and useful Improvements in Sewing-Machine Shuttles, of which the following is a specification.

This invention relates to a shuttle which includes a body movable in a shuttle race, and a bobbin case separably engaged with the body, the case being closed at one end by a head and having a tubular post, which receives a bearing post on the body when the parts are assembled.

A bobbin usually of the ready-wound variety, is enclosed in the case between the head thereof and a portion of the body.

A shuttle embodying the invention is characterized by the improved means, hereinafter described and claimed, for preventing undesirably free rotation of the bobbin, and for partly ejecting the same, or a cop tube forming a component part thereof, from the case, when the latter is separated from the body.

Of the accompanying drawings forming a part of this specification,—

Figure 1 is a side view of a shuttle body to which the invention relates.

Figure 2 is a section on line 2—2 of Figure 1.

Figure 3 is a perspective view of the end-thrust supporting disk fixed to the bearing post, as hereinafter described.

Figure 4 is a fragmentary sectional view, showing a portion of the body, a portion of the bearing post and the end-thrust supporting disk before the latter is rigidly secured to the bearing post.

Figure 5 is a view similar to Figure 4, showing the end-thrust-supporting disk rigidly attached to the bearing post, and a tool adapted to cause such attachment.

Figure 6 is a sectional view, showing assembled the shuttle body as in Figure 2, and the bobbin case and its contents.

Figure 7 is an enlarged sectional view, showing the bobbin case and the veneering disk hereinafter described, the locking means being omitted.

Figure 8 is a perspective view of the veneering disk.

Figure 9 is a perspective view of the frictional bobbin pressing member herein-after described.

Figure 10 is a perspective view of the stop sleeve hereinafter described.

Figure 11 is a sectional view, showing the bobbin case, its contents or adjuncts shown by Figures 8, 9, and 10, and a bobbin partly projected from the case, the locking means being omitted.

The same reference characters indicate the same parts in all the figures.

In the drawings, 12 designates a shuttle body, which may be of any suitable form, and is provided with a bearing post 13, and with a bobbin-case receiving space through which said post extends. There is nothing new with me in the shuttle body and its post, so that the partial representation thereof in Figures 1, 2 and 6 is considered sufficient for the purposes of this specification.

The bobbin case is composed, as usual, of an annular wall or curb 14, open at one end and closed at the opposite end by a head 15, supporting and surrounding the inner end of a central tubular post 16, which is formed to receive the body post 13. The head and the body post may be provided with any suitable means, adapted to releasably confine the bobbin case on the inner post. Said means may include a sliding latch 17, shown in section, adapted to engage a groove 18, in the body post, the latter projecting through an opening in the head, the latch springing as usual, into the groove, to confine the case, and being displaceable to release the case.

In carrying out my invention, I combine with the shuttle body and bobbin case, the series of members next described, adapted to cooperate with a bobbin of the ready-wound type, such as that shown by Figures 6 and 11. Said bobbin may comprise a core or cop tube 19, usually of paper, and a winding 20 of thread, universally wound on the tube.

The bearing post 13 is provided, as usual, in shuttles of this type, with an annular enlargement 21, surrounding the base of the post. I utilize this enlargement as an element of means for rigidly securing to the post a thrust bearing-supporting disk 22,

adapted to bear on the outer end of the bobbin and support the thrust exerted thereon, by pressing means within the bobbin case. The disk 22 is provided with a central opening 23 and with an upstanding annular flange 24, surrounding the opening. The internal diameter of said flange is slightly less than the diameter of the enlargement 21, so that when a swaging tool 25, formed as shown by Figure 5, is driven against the disk, the latter is forced from the position shown by Figure 4, to that shown by Figure 5. The flange is thus driven tightly upon the enlargement, so that 15 the disk is rigidly secured to the post 13.

Interposed between the case head 15 and the space occupied by the bobbin is a frictional member adapted to press the outer end of the bobbin against the end thrust supporting disk 22. Said member comprises a pressing disk 26, of thin resilient sheet metal, such as steel, adapted to bear on the inner end of the bobbin and having a central opening 26', loosely receiving the 20 tubular post, and a plurality of resilient tongues 27 integral with the pressing disk and inclined from the inner surface thereof to cooperate with the case head in yieldingly pressing the pressing disk against the 25 bobbin, and the bobbin against the end thrust supporting disk 22.

The diameter of the pressing disk is so nearly equal to the internal diameter of the case, that it prevents the possibility of loose 30 coils of thread unwound from the bobbin from entering the space between the bobbin and the head, and being caught or entangled.

While the tongues 27 may contact directly with the inner surface of the head 15, the fact that the head is usually provided with slots or openings 28, for well known purposes, renders such direct contact objectionable, because of liability of the tongues to engage the edges of the slots, and thus prevent the free rotation of the pressing plate 40 with the bobbin. I therefore preferably provide a smooth surfaced annular veneering disk 29, which contacts with the inner side of the case head and covers the slots 28 as 45 shown by Figure 7, the tongues 27 contacting with the veneering disk, as shown by Figure 11, and being slidable thereon.

The tubular post 16 is provided, as heretofore, with a split resilient stop sleeve 30, 55 adapted to yieldingly embrace the post and be adjustably secured thereon by friction. The inner end of the stop sleeve abuts against the pressing disk 26, and arrests the outward movement thereof by the tongues 60 27, the arrangement being such that the pressing disk may be moved outward sufficiently to project one end of the bobbin from the case, as shown by Figure 11, so that the bobbin may be conveniently removed when 65 the case is removed from the shuttle body.

It is obvious that the end thrust-supporting disk 22 may be employed with other pressing means for exerting outward pressure on the bobbin, and that said disk may be slightly dished as shown, or flat, according to the form of the bobbin ends. The disk 22 may be rigidly secured to the post or the shuttle body by other means, the means shown being preferred, because of its simplicity, and the fact that it includes the 75 usual post enlargement 21.

The bobbin pressing means comprising the pressing disk 26 and resilient tongues 27, is extremely compact, and occupies less than one-half of the space required by the volute 80 spring which has been heretofore interposed between the case head and the bobbin-containing space in the case. The action of said pressing means is very quick and sensitive. It may be employed in conjunction with other end thrust-supporting means, such as the portion 12^a of the shuttle body. The disk 22 is preferred, however, because it presents a large area of bearing surface uniformly distributed around the post. The shuttle body shown by the drawings is that of the well known S. C. B. shuttle. It is obvious that the adjunct may be reversed, from the position shown by Figure 6, so that the pressing disk 26 bears on the head 15, and the veneering disk 29 bears on the adjacent end face of the bobbin, the veneering disk preventing contact of the tongues with the relatively rough and yielding end face of the bobbin.

The bobbin pressing disk 26 and its resilient fingers, may be used in nearly every shuttle which is commonly provided with a volute spring exerting outward pressure on the bobbin. Said disk not only prevents the possibility of coils of thread being caught in the shuttle case as above stated, but also presents a flat outer surface, entirely covering the inner end of the bobbin, and pressing uniformly against all parts of said end by the spring tongues. The tongues 27 may be forced back into the slots 27^a, formed in the disk by the operation of forming the tongues, so that when the tongues are fully compressed, the thickness of the bobbin-pressing member is practically no greater than that of the sheet metal from which it is formed.

I claim:

In combination, a shuttle comprising a head forming one end of a bobbin-receiving cavity, a central post in said cavity, on which a bobbin in the cavity is rotatable, a thrust support for the bobbin at the opposite end of the cavity, the inner face of said head and an end face of the bobbin being spaced apart within the cavity when the bobbin bears on the thrust support, and a bobbin-controlling adjunct interposed between said faces, and including a smooth surfaced annular veneer- 120

ing disk surrounding the post and bearing on one of said faces, an annular pressing disk of thin resilient sheet metal surrounding the post and bearing on the other of said faces, and a plurality of resilient tongues integral with the pressing disk and inclined from one of the sides thereof to bear on the veneering disk and maintain

the two disks yieldingly spaced apart, the tongues being tensioned by the bobbin when 10 the shuttle is in use, and acting to press the bobbin against the thrust support.

In testimony whereof I have affixed my signature.

LUCIUS E. WEAVER.
